UNITED STATES PATENT OFFICE.

EDWARD C. CAPPER, OF DUMONT, IOWA.

POWER PLANT.

1,091,188.

Specification of Letters Patent. Patented Mar. 24, 1914.

Application filed May 6, 1912, Serial No. 695,565. Renewed February 6, 1914. Serial No. 817,081.

To all whom it may concern:

Be it known that I, EDWARD C. CAPPER, a citizen of the United States, residing at Dumont, in the county of Butler and State of Iowa, have invented a new and useful Power Plant, of which the following is a specification.

The object of my invention is to provide a power plant of simple and durable construction whereby steam may be generated by use of gasolene and in which all the heat of the gasolene is utilized.

More particularly, it is my object to provide a power plant including a steam boiler in which flues are dispensed with and in which is mounted a receptacle containing a gasolene or other burner.

A further object is to provide a power plant in which the products of combustion are discharged with the steam.

A further object is to provide a boiler of the kind described, and a burner of the kind mentioned in a receptacle in the boiler, and to provide means for forcing the fuel into the burner under pressure and for mixing air with the fuel as the latter is fed to the burner.

My invention consists in certain details, in the construction, arrangement and combination of the various parts of my device, whereby the objects contemplated are attained, as hereinafter more fully set forth, pointed out in my claims, and illustrated in the accompanying drawings, in which—

Figure 1 shows a side elevation of a power plant embodying my invention, some of the parts being broken away to show the interior mechanism of the boiler and the burner. Fig. 2 shows a vertical, transverse, sectional view through the burner tube.

In the accompanying drawings, I have used the reference numeral 10 to indicate a storage tank for compressed air which may be supplied through the tube 11. On the tank 10 is a pressure gage 12 and a safety valve 13. Near the tank 10 is a boiler 14 on which is a steam dome 15 communicating with which is a discharge pipe 16. On the steam dome is a steam gage 17. The boiler 14 is designed to contain water 18. Mounted within the boiler is a receptacle 20 which may be cylindrical in form as shown and is designed to be ordinarily wholly surrounded by the water in the boiler. A pipe 19 communicates with the tank 10 and extends through the end of the boiler 14 and through

the wall of the receptacle 20. Mounted on the end of the pipe 19, preferably below the same is a burner 21 which may be in the form of a pipe or cylinder having slots 22 in its lower surface.

Communicating with the interior of the receptacle 20 and extending upwardly therefrom into the steam dome 15, is a tube 22 designed to carry the products of combustion into the steam dome.

Mounted on the boiler 14 or in any suitable place is a fuel tank 24 filled with gasolene 25 or other suitable fuel to a point near its upper end. In the upper end of the tank 24 is an opening which may be covered by an air tight, detachable cap 23. A tube 26 connects the upper portion of the interior of the tank 10 with the upper portion of the interior of the tank 24. A tube 27 connects the lower portion of the tank 24 with the tube or pipe 19. In the pipe 27 is a valve 28 and in the pipe 19 between the tube 27 and the tank 10 is a valve 29.

Communicating with the interior of the receptacle 20 and extending to a point outside the wall of the boiler 14, is a tube 30 which may be internally screwthreaded, as shown. In the tube 30 is a spark plug 31 extending through which is an electrode 32, the upper end of which is slightly spaced apart from the electrode 33, which may be grounded on the tube 30, thus forming a spark gap between the electrodes 32 and 33.

At a suitable point is placed a battery 34, one wire 35, of which is connected with the electrode 32 and the other wire 36, of which is connected with the boiler 14.

It will be understood that the tube 30 and the receptacle 20, the boiler 14 and the brackets 38, by which the receptacle 20 is mounted in the boiler, are made of conducting metals or at least are connected by conducting metals.

On the battery 34 is a suitable switch 37. At a suitable point below the tube 19 is a generator 39. On the boiler is a water gage 40.

The practical operation of my improved power plant is as follows: Fuel is placed in the fuel tank 24 until the tank is almost filled. The air is pumped into the tank 10. The discharge of fuel and air from the tanks 24 and 10 is regulated by the valves 28 and 29. The boiler is filled with water. By operating the valves 28 and 29, fuel and air may be mingled in the pipe 19. The generator 39 may be used to vaporize the gaso-

lene, which may be lighted within the receptacle 20 by a spark from the battery 34. As the water is heated, the steam passes into the steam dome and the products of combustion at the same time pass into the steam dome through the tube 22 and mingle with the steam. The steam may be drawn from the dome 15 and used as desired.

As will be seen from the foregoing description, the arrangement and construction of my power plant enables me to dispense with the tubes which are one of the expensive features of the ordinary steam boiler. On account of the fact that the receptacle 20 is in the water in the boiler, and that the discharge of products of combustion is into the steam, I am able to utilize all the heat generated from the burner 21. Air under pressure may be mixed with the gasolene as desired.

My power plant effects a great saving in cost of construction and in the amount of fuel necessary to produce a given amount of steam. The parts are simple and are not likely to wear out.

I claim as my invention:

1. In a device of the class described, the combination of a boiler, a receptacle therein designed to be submerged in the water in said boiler, a burner in said receptacle, a tank designed to contain air under pressure, a pipe leading from said tank through the walls of the boiler and the receptacle to said burner, a fuel supply tank, a tube connecting the upper end thereof with said air tank, a tube connecting the lower end of said fuel tank with said pipe, a valve in said last named tube, a valve in said pipe between the last named tube and the air tank, means for carrying off the products of combustion from said receptacle with the

steam from said boiler, a generator cup on the outside of said boiler arranged below the pipe leading to said burner for the purpose of generating the fuel within said pipe, and means whereby the generated fuel in said burner may be ignited from outside the boiler.

2. In a device of the class described, the combination of a horizontal boiler, a receptacle therein designed to be submerged in the water in said boiler, a burner pipe longitudinally arranged within said receptacle, a tank designed to contain air under pressure, a pipe leading from said tank through the walls of the boiler and the receptacle to said burner, a fuel supply tank, a tube connecting the upper end thereof with said air tank, a tube connecting the lower end of said fuel tank with said pipe, a valve in said last named tube, a valve in said pipe between said last named tube and the air tank, a generator cup on the outside of said boiler arranged below the pipe leading to the burner for the purpose of generating the fuel within said pipe, a tube communicating with said receptacle adjacent to the burner and extending outside of said boiler, a spark plug arranged in said tube, a battery electrically connected with said spark plug to thereby provide a spark near said burner for igniting the generated gas therein, and means for carrying off the products of combustion from said receptacle with the steam from said boiler as and for the purposes stated.

Des Moines, Iowa, April 29, 1912.

EDWARD C. CAPPER.
